UNITED STATES PATENT OFFICE.

CHARLES W. HARROLD, OF WARREN, OHIO, ASSIGNOR TO THE HARRIS AUTOMATIC PRESS COMPANY, OF NILES, OHIO, A CORPORATION OF OHIO.

BAG-FEEDER.

1,191,966.

Specification of Letters Patent. Patented July 25, 1916.

Application filed October 29, 1915. Serial No. 58,667.

To all whom it may concern:

Be it known that I, CHARLES W. HARROLD, of Warren, in the county of Trumbull and State of Ohio, have invented certain new and useful Improvements in Bag-Feeders; and I do hereby declare the following to be a full, clear, and exact description of the invention, such as will enable others skilled in the art to which it appertains to make and use the same.

The primary object of this invention is to provide simple and highly efficient means for separating the topmost bag or bag-tube from a pile or stack thereof, preparatory to feeding it to a printing-press or other bag-handling machine.

According to my invention restraining pressure is applied at or near one longitudinal side of the pile, on the top thereof, and 20 preferably near one corner, and by introducing a separating element between the upper and lower portions of the top-most bag-tube, the other longitudinal edge of the latter, at the opposite side of the pile, will 25 be drawn inwardly a sufficient distance to clear a hold-down element, whereupon as the separating element is withdrawn the raised or separated edge of the bag-tube will 30 be prevented from returning to the pile. The separated bag-tube may then be fed from the pile.

In the accompanying drawings, Figure 1 is a top plan view showing my improvement. Fig. 2 is a view in side elevation of 35 the parts shown in Fig. 1. Fig. 3 is an end view of a pile of bag-tubes showing the separator in engagement with a bag-tube. Fig. 4 is a view similar to Fig. 3 but with the separator withdrawn and the feeding means 40 in position to engage the edge of the bag-tube.

Referring to the drawings, 1 designates a stack or pile of bag-tubes which may be maintained at practically a constant level 45 by any suitable or known means. The longitudinal axis is preferably at right angles to the feed-path to a printing press or other bag-handling machine. The top of the pile is engaged by a presser 2 which is designed 50 to bear against the topmost bag-tube at a point near one edge of the pile, and preferably in close proximity to one of the corners. The pressure exerted must be sufficient to prevent any bodily displacement of the

topmost bag while such presser maintains a 55 fixed relation to the pile. I also provide an additional hold-down 3, for engaging the opposite edge of the pile. This hold-down, as shown, is designed to be removed and then returned to the top of the pile, while 60 the presser 2 maintains pressure on the pile, but it may be held in fixed relation to the pile provided it exerts less friction thereon than the presser 2. One hold-down 3 will suffice but more may be used. 65

5 designates a reciprocating separating member which is designed to enter between the two sides, or upper and lower portions, of the topmost bag-tube, and by moving inwardly a sufficient distance separate the 70 upper and lower portions of the bag-tube to such an extent as to draw the one edge thereof upwardly and forwardly from beneath the hold-down 3. This withdrawal of the edge of the bag-tube is rendered possible only by maintaining pressure on the top 75 of the pile through the medium of presser 2. In the form illustrated, while the edge of the topmost bag-tube is raised and drawn inwardly, as clearly shown in Fig. 3, the 80 hold-down 3 is returned to its normal position in engagement with the top of the pile. As the separating element 5 is withdrawn from the bag-tube and the sides thereof come together it will fall against and rest 85 upon the hold-down 3. In this way the edge of the topmost bag-tube is held sufficiently above the top of the pile or stack to enable the bag to be engaged by suitable means, such as indicated at 6, and removed from 90 the pile. In the form shown this is facilitated by moving presser 2 from engagement with the pile. By the time the bag is removed from the pile the presser is again moved into engagement with the pile so as 95 to exert the necessary pressure thereon before the separating element 5 acts on the next bag-tube to a sufficient extent to draw the edge thereof inwardly and forwardly as before described. 100

Any suitable means may be employed for manipulating the various parts, that is to say, for raising and lowering the presser and hold-downs; for reciprocating the separating element; and for removing the topmost or separated bag-tube from the pile. 105

The advantages of my invention will readily be appreciated by those skilled in

the art, and it will be observed that by means thereof I am enabled to easily and positively insure the separation of the topmost bag from a stack thereof.

- 5 I do not restrict myself to any particular construction for carrying out this invention, since it is manifest that any suitable means may be employed for applying sufficient pressure against the top of the pile to insure
- 10 the withdrawal of one edge of the topmost bag-tube from its normal position and for preventing it from returning to its former position after the separating means has been withdrawn. By "top of the pile" is meant
- 15 that portion of the pile adjacent the separating means, and "topmost bag-tube" refers to that bag which is directly in position to be acted upon by the separating means.

I claim as my invention:

- 20 1. In a bag-tube feeder, means for applying pressure against the top of a pile of bag-tubes near one side thereof, means for separating the two sides of the topmost bag-tube while pressure is applied thereto by the
- 25 first mentioned means, such separating means serving to raise and draw inwardly one longitudinal edge of the topmost bag-tube, and means for removing said bag-tube from the pile.
- 30 2. In a bag-tube feeder, means for applying pressure against the top of a pile of bag-tubes near one side thereof, means for separating the two sides of the topmost bag-tube while pressure is applied thereto by the first
- 35 mentioned means, such separating means serving to raise and draw inwardly one longitudinal edge of the topmost bag-tube, and feeding means for engaging said longitudinal edge.
- 40 3. In a bag-tube feeder, means for applying pressure against the top of a pile of bag-tubes near one side thereof, means for entering between the upper and lower sides of the topmost bag-tube while pressure is applied thereto by the first mentioned means, a hold-down member for engaging the pile,
- 45

and means for engaging and feeding such topmost bag-tube from the pile.

4. In a bag-tube feeder, means for applying pressure against the top of a pile of bag-tubes near one side thereof, means for entering between the upper and lower sides of the topmost bag-tube while pressure is applied thereto by the first mentioned means, a hold-down member for engaging the pile 55 near the other side thereof and upon which the topmost bag-tube is designed to rest, and means for engaging and feeding such topmost bag-tube from the pile.

5. In a bag-tube feeder, means for applying pressure on the top of a pile of bag-tubes near one of its corners, means for entering between the two sides of the topmost bag-tube and drawing one side edge toward the side upon which such pressure is applied, 60 hold-down means engaging such pile when such topmost bag-tube is moved by said entering means, and means for feeding the topmost bag-tube from the pile.

6. In a bag-tube feeder, a presser member 70 for engaging the top of a pile of bag-tubes near one side thereof, means for separating the upper and lower portions of the topmost bag-tube while the latter is engaged by said presser member for drawing the longitudinal edge of said topmost bag-tube 75 away from the other side of the pile, a hold-down member for engaging the pile when said topmost bag-tube is drawn away from said side and upon which said bag-tube is 80 designed to rest when said separating member is withdrawn, and means for engaging and feeding such topmost bag-tube from the pile.

In testimony whereof, I have signed this 85 specification in the presence of two subscribing witnesses.

CHARLES W. HARROLD.
